UNITED STATES PATENT OFFICE.

GEORGE W. KRAMER, OF PEORIA, ILLINOIS.

FEEDER AND STRIKE-OFF DEVICE FOR CEMENT BLOCKS.

1,184,356.

Specification of Letters Patent.

Patented May 23, 1916.

Application filed January 13, 1913. Serial No. 741,831.

To all whom it may concern:

Be it known that I, GEORGE W. KRAMER, a citizen of the United States, residing at Peoria, in the county of Peoria and State of Illinois, have invented certain new and useful Improvements in Feeder and Strike-Off Devices for Cement Blocks, of which the following is a specification.

This invention has reference to a self-feeding and troweling or strike-off device for use in concrete block manufacture.

The present invention has for its object, to provide a device, for use in connection with concrete block tamping machines, which is adapted to receive material from a mixer; deliver the material to the block machine or mold, and when the block is finished, strike-off and trowel the block in one operation, accumulating the surplus material struck off, for a subsequent block.

The invention has for a further object, a troweling or strike-off device for concrete block making machines including a revolving member, such as a roller, geared to rotate at considerable speed and preferably, arranged to rotate in a direction opposite to its travel over a block, and capable of striking off a block and leaving a smooth finish, even though the material is very coarse.

My invention is adapted for use in connection with various block machines or molds, and particularly in connection with tamping machines such as shown in the patents granted to me on January 17th, 1911, numbered 981,928 and 981,929.

That the invention may be more fully understood reference is had to the accompanying drawings, in which:

Figure 1 is a side elevation of my self-feeding and troweling or strike-off device, certain gearing and other instrumentalities for operating the same being omitted and showing a part of a continuous mixer for supplying material to the device, a part of a block machine or mold and the tampers, the parts shown in the forward position of their movement; Fig. 2 is a longitudinal sectional view of the device, as the same would appear, if taken on the line 2-2 of Fig. 5, the parts in the same position shown in Fig. 1 and showing the block machine or mold in section with a concrete block at the completion of the tamping operation; Fig. 3 is a view similar to Fig. 2, except that the tampers have been raised out of position and the device is shown moving backward

and the roller striking off and troweling the concrete block and accumulating the surplus material for a subsequent block; Fig. 4 is a cross-section of the device, as the same would appear, if taken on the line 4-4 of Fig. 5; Fig. 5 is a plan view of the device, shown in Fig. 1, with the gearing and other instrumentalities for operating and controlling the same, parts being broken away, and other parts in section; Fig. 6 is a side elevation of the gearing and other instrumentalities for operating and controlling the movement of the device shown in Fig. 1; Fig. 7 is a longitudinal sectional view through the gearing, as the same would appear, if taken on the line 7-7 of Fig. 5; Fig. 8 is a cross-section, as the same would appear if taken on the line 8-8 of Fig. 6; Fig. 9 is a cross-section, as the same would appear if taken on the line 9-9 of Fig. 6; Fig. 10 is a rear end view looking at the right hand end of Fig. 6, and Fig. 11 is a plan view of certain clutch operating means.

Like characters of reference denote corresponding parts throughout the figures.

In Fig. 1 the device is shown moved to a forward position delivering material into the block machine or mold and stopped preparatory to the operation of the tampers. The block machine or mold which is only partly shown, is designated A, and may be of any preferred construction, the tampers as B, and may be of any preferred construction, and a continuous mixer as C, and may be of any preferred construction. This continuous mixer C is so placed that it will deliver mixed material direct into the hopper of my troweling or strike-off device, which in turn delivers the material into the block machine or mold, and when the block is finished or has been tamped, strikes off the block and returns the surplus material to the hopper, thus preventing the surplus material falling from the machine onto the floor or platform.

The self-feeding and troweling or strike-off device proper, includes the stationary hopper part 12 and the movable or traveling feeder portion 13, adapted to be mounted or supported in any suitable manner, in connection with a tamping machine, such for instance as illustrated in Patent No. 981,928 and any suitable block machine or mold.

The hopper part 12, comprises the side walls 14, the front wall 15 and the sloping rear wall 16 and these walls at their meet-

- ing corners are braced and reinforced by the angle bars 17. The bottom or supporting plate for the front, side and rear walls of the hopper is designated as 18 and when in operative relation with the block machine or mold A is secured thereto as at 19. The side walls, where they unite with the bottom or supporting plate 18 are braced and reinforced by the angle bars 20.
- 10 The movable or traveling feeder portion 13, comprises the side plates 21, of suitable length, preferably considerably longer than the length of the hopper 12; said plates 21 lie between the hopper and adjacent to the 15 inside faces of the side walls 14 of the hopper, see Fig. 4 and movable through the hopper. The front wall 15 of the hopper stops short of the upper edges of the plates 21, see Fig. 2 and the rear sloping wall 16 20 of the hopper is cut away, as at 22, see Fig. 4 to allow the plates 21 to travel back and forth. The side walls 14 of the hopper serve as guiding means for the plates 21 in conjunction with the angle bars or brace members 23, extending the length of the plates 21, see Figs. 1 and 4. Said angle bars or brace members 23 are preferably spaced from and secured at their opposite ends to the plates 21 through interposed members 24, see Figs. 1 and 5, so as to provide space 25 between the angle bars 23 and the plates 21 to allow for the travel of the plates 21 and to guide the same, the side walls 14 of the hopper fitting in said spaces. The plates 21 30 are connected at their forward ends by the cross-head or front wall 25, braced and reinforced at the corners by the angle bars 26.
- 35 The hopper 12 has a false bottom, consisting of the plate 26^a, removed a suitable 40 distance above the bottom or supporting plate 18 and extending between and secured to the side plates 21 of the movable feeder 13, through the medium of the longitudinal angle bars or reinforcing plates 27. The 45 bottom 26^a is movable with the feeder 13 and is of sufficient length to form a closure for the bottom of the hopper 12 when the feeder is advanced and when the feeder is retracted moves to a position to allow the 50 material deposited in the hopper proper, to fall down onto the stationary bottom or supporting plate 18. The false bottom 26^a has a front wall 28, see Figs. 2 and 3, and the space in the feeder 13 between the front 55 wall 28 and the front end of the feeder, or strike-off or troweling device, to be described, provides an opening through the feeder, through which the material is discharged from the feeder into the block machine or mold A, therebeneath, when the 60 feeder has moved with such opening therein into coincidence with said block machine or mold A. The front wall 28 at the corners is braced or reinforced by the angle bars 29. 65 The position of the front wall 28 from the

front end of the feeder, or strike-off or troweling device, to be described, determines to a certain extent, the quantity of material to be discharged from the feeder into the block machine or mold, and said front wall 70 28 and false bottom 26^a may be adjustable or substitutes provided therefor, as may be desirable.

75 The strike-off or troweling device, includes the roller 30, located at the forward end of the feeder 12 and extending transversely thereof, see Figs. 2 and 3 and mounted to rotate with a driven shaft 31 journaled in the side plates 21. The lower surface of the roller 30 is approximately 80 flush with the upper surface of the block machine or mold A, see Figs. 2 and 3, so that when the feeder is traveling backward, after a block forming operation, the roller 30 will strike off the block and leave a 85 smooth surface, see Fig. 3. A shield 32 covers the upper surface of the roller 30, and is attached or secured to the front wall 25 of the feeder. Shields 33 are also provided to cover the upper edges of the plates 90 21, these shields being secured to the inside faces of the side walls 14 of the hopper, see Figs. 2, 4 and 5.

95 The feeder 13 is held from lateral motion by the side walls 14 of the hopper and the bars 23 coöperating therewith, as described, and to guide and prevent any lifting motion of the feeder, during its travel, except at a predetermined movement of said feeder, I provide rollers 34 journaled to the outside 100 faces of the side walls 14 of the hopper, see Figs. 1 and 5, engaging the upper faces of the angles 23, and the rollers 35 journaled to the outside faces of the side walls 14 of the hopper, see Fig. 1, engaging the lower 105 faces of the angles 23.

110 In the present structure where the bottom or supporting plate 18 is secured to the block machine or mold A, said plate 18 has a sloping surface 36, see Figs. 2 and 3. As the feeder recedes and as it reaches the end of its backward movement, the roller 30 travels up over the sloping surface 36, raising the front end of the feeder and the side plates 21, and to allow for this movement, the angles 23 are cut away at 37, see Fig. 1. There are certain types of block machines or molds, where the slight vertical movement of the feeder will not be necessary.

115 I will now describe the gearing and other instrumentalities which I employ for operating the feeder 13 and the strike-off or troweling device 30.

120 Attached to the inside faces of the plates 21, below the false bottom 26^a and extending longitudinally thereof for a suitable distance, are rack bars 38 made integral with or attached to angle bars 39. Meshing with these rack bars 38 are gear wheels 40 carried on a drive shaft 41, and operating through 125 130

openings 42 in the bottom or supporting plate 18, see Fig. 4. The shaft 41 is journaled in boxings 43, secured to the underside of the bottom or supporting plate 18. It is 5 obvious that if the shaft 41 be rotated in reverse directions it will move the rack bars 38 through the medium of the gears 40 in a forwardly and then in a rearwardly direction and move the feeder 13 and plates carried thereby in similar directions. The 10 shafts 41 and 31, the latter carrying the strike-off or troweling roller 30, are driven from reversible gearing which is controlled by certain instrumentalities for intermittently placing such gearing in a neutral position.

Reference being had to Fig. 5 it will be observed that the shaft 31 is coupled up with a driving shaft 44, and the shaft 41 is coupled up in a similar manner with a drive shaft 45. Said drive shafts 44 and 45 are journaled in a suitable frame-work supporting the gearing for operating the feeder 13, and such frame-work may be an independent structure or a part of the frame carrying the tamping mechanism or the frame of the block machine or mold. The 25 coupling between the shafts 31 and 44 includes the interposed shaft 46 and the knuckle joints 27 to produce a flexible connection and in a like manner the coupling between the shaft 41 and the shaft 45 includes the interposed shaft 48 and the knuckle joints 49. 30 50 designates the main drive shaft carrying a pulley 51 by means of which the shaft 50 may be driven from any suitable source of power. On this main drive shaft 50 are loosely carried beveled gear wheels 52 and 40 53 provided with the internal beveled frictional clutch faces 54. Adapted to have a frictional engaging relation with either the gear 52 or the gear 53 is a clutch member 55 provided with the oppositely disposed engaging portions 56 and 57 adapted to be thrown into engagement with the friction surface 54 of the gear 52 or the friction surface 54 of the gear 53 to place the same in driving relation with the main driving 45 shaft 50. The clutch member 55 is carried so as to slide on the main driving shaft 50 so as to place either of the gears 52 or 53 in driving relation with said shaft. The clutch 55 is provided with a centrally disposed annular depression or seat 58 in which is carried the bifurcated end 59 of an operating member 60. The member 60 is attached to a shiftable rod 61 having a bearing in the frame-work of the machine and connected 50 with said operating member 60 is the forward end 62 of an operator's lever 63. It is therefore obvious, that if the shiftable rod 61 is moved either to the right or left, it will in turn move the operating member 60 in the direction of movement of said rod

61 and place the clutch 55 in driving relation with either of the gears 52 or 53. The lever 63 is fulcrumed at 64 to a suitable part of the frame to facilitate in the operation of said lever for moving the shiftable rod 61 70 in the manner specified.

The gears 52 and 53 are in constant meshing relation with a beveled gear wheel 65 carried by a short shaft 66, on the outer end of which is a bevel gear wheel 67 meshing 75 with a bevel gear wheel 68 on the driving shaft 44. This connection from the gear wheels 52 and 53 to the drive shaft 54 will operate said shaft 54 in reverse directions, depending of course on the connection of the clutch 55 with either of said gears 52 or 53. Said gears 52 and 53 are also in constant meshing relation with a bevel gear wheel 69 carried by a short shaft 70, journaled in a suitable part of the frame, and said shaft 70 carries a worm 71 in meshing relation with a worm wheel 72 on the drive shaft 45. It is obvious that the drive shaft 45 will revolve in opposite directions, depending of course on the connection of the clutch 55 90 with either of the beveled gear wheels 52 or 53.

The driving connection between the main shaft 50 and the shaft 44 is such that said shaft 44 may be rotated at a considerably 95 greater speed than the shaft 45 through its driving connection with said main driving shaft 50. This is for the purpose, as will be understood, of rotating the strike-off or troweling roller 30 very rapidly, while at the same time moving the feeder 13 at a very slow speed.

I have provided in connection with the gearing described, instrumentalities for automatically moving the clutch 55 to a neutral position at predetermined intervals, in the movement of the feeder 13; said instrumentalities operating preferably at the moment when the feeder 13 reaches the limit of its forward movement, being substantially 105 that position shown in Fig. 2; and at the limit of its rearward movement, being that position when the roller 30 has struck off or troweled a block, or is in a position with the front wall of the false bottom 26^a far enough 110 back to where the material will pass from the hopper 16, on to the bottom of the supporting plate 18, to be carried forward by said front wall 28 during the forward movement 115 of the feeder 13 and discharged in the block machine or mold A. The mechanism referred to comprises a pair of disks 73 and 74 secured to the driving shaft 45 and placed on opposite sides of the worm wheel 72. To these two disks 73 and 74 are attached corresponding lugs or fingers 75, which are preferably adjustably connected with the disks and spaced on the disks 73 and 74 to operate alternately upon means to be described for automatically throwing the op- 120 125 130

erating or clutch arm 59 at predetermined intervals of the movement of the feeder 13. 76 and 77 are movable plates, each slotted at 78, as shown in Fig. 6, to have movement 5 crosswise of the shaft 45, and the plates 76 and 77 lie adjacent or in juxtaposition to the respective disks 73 and 74, see Fig. 5, and said plates are arranged with projecting lugs or fingers 79, see Figs. 5, 6, 9 and 10, 10 which overlie the peripheries of the disks 73 and 74, so that during the rotation of said disks the lugs or fingers 75 thereon will come into engaging relation with the lugs or fingers 79 and move the plates 76 and 77. The 15 plate 76 is integral with or has attached thereto a bar 80 which extends forward and has a pivotal connection at 81 with a member 82 connected with the lever 63; and the plate 77 is integral with or has attached 20 thereto a bar 83 which extends forward and has a pivotal connection at 84 with the said member 82. Thus it will be seen that if the lever 63 has been moved to place the clutch 55 into operative relation with either of the 25 gears 52 or 53, that the movement of the plate 76, or the plate 77, by the means described, will automatically throw the lever 63 and the clutch 55 to the neutral position shown in Fig. 8, placing the gears 52 and 30 53 in an inoperative relation with the main drive shaft 50. The lugs or fingers 75 on the respective disks 73 and 74 are presumed to be adjusted on said disks so that when the feeder 13 reaches the limit of its forward 35 movement, one of said disks will operate to place the clutch 55 into a neutral position, and in like manner when the feeder 13 has been retracted a suitable distance, one of 40 said disks will operate to move the clutch 55 into a neutral position to stop the movement of the feeder 13. It is intended, that the operator, by means of the lever 63 shall have control of and place the clutch 55 into operative engagement with either of the gears 45 52 or 53 and that the disks 73 and 74 co-operating with the plates 76 and 77 will alternately move the clutch 55 to a neutral position. In the present arrangement, with the clutch 55 in operative engagement with 50 the gear 52, the feeder 13 is moved forwardly, and when the clutch 55 is in operative engagement with the gear 53 the feeder 13 will be moved rearwardly. When the feeder 13 is moved forwardly, the strike-off 55 or troweling roller 30 will be positively rotated in a clockwise direction and when the feeder 13 is being moved rearwardly said strike-off or troweling roller 30 will be positively driven in an anti-clockwise direction.

Reference being had to Figs. 2 and 3, 85 is 60 a swinging valve plate pivoted at 86 to adjustable hangers 87 suitably secured to the inside of the front wall 15 of the hopper 12. This valve plate is suspended in a manner to swing inward and upward with its lower 65 edge normally spaced a short distance above the upper face of the false bottom 26^a in the feeder 13. This valve plate, to a certain extent limits the quantity of material which passes with the feeder forwardly to the 70 block machine or mold A, and when the feeder is moving rearwardly and the roller 30 is striking off the block it will swing sufficiently to allow the surplus material to back up into the hopper 12. 75

I am aware of manually operated strike off devices for concrete block-machines but with the use of such machines there is considerable loss of material, or if not actual loss, the material struck off from the block falls on the floor or platform supporting the machine and the material must be rehandled, making the operation slow and tedious. With the use of my device such inconveniences and delays are entirely obviated. 80 Then again, with the use of strike off devices heretofore made, it has been very difficult to leave a smooth surface on the block should the mixture or material contain any large pebbles or stones, without retrograding 85 the surface of the block. Using a revoluble strike-off, such as I do, and rotating the same in a direction reversely to the travel of the feeder, when the roller comes into contact with the stone or pebble, it will either force it down into the mold or throw it up 90 into the hopper. 95

What I claim is:—

In an apparatus of the character described and in combination, a feeder adapted to be reciprocated for moving material from a supply to a block machine or mold, a rotatable strike-off member connected to said feeder to move therewith, operating means to reciprocate said feeder and to positively rotate said strike-off member, clutch mechanism for controlling said operating means and means for automatically disengaging said clutch mechanism when the feeder reaches the limit of its forward movement and when the feeder reaches the limit of its rearward movement. 100 105 110

In testimony whereof I affix my signature, in presence of two witnesses.

GEORGE W. KRAMER.
